AIR VENTED TANK DRAIN

Melvin N. Johnson, Faribault, Minn.

Application March 26, 1941, Serial No. 385,219

3 Claims. (Cl. 285—208)

My invention provides an extremely simple and highly efficient air vent tank drain, the elements of which are assembled as a common unit. While adapted for quite general use, the improved device is especially designed for use as a ventilating tank drain for hot water heating systems wherein a closed pressure tank is employed.

One of the objects of the invention is to provide a combined drain faucet and air vent that may utilize the standard or commercial pipe fitting such as may be purchased on the market or adapted for various uses by plumbers, steam fitters and the like, and wherein the pipe fitting may be easily used for the application of an air vent tube thereto.

Generally stated, the invention consists of the novel devices, combinations of devices, and arrangement of parts hereinafter described and defined in the claims. In the accompanying drawing which illustrates the invention, like characters indicate like parts throughout the several views.

Referring to the drawing:

Fig. 1 is a view in elevation outlining a water heating system including a closed pressure tank 25 equipped with my improved air vent tank drain, some parts being broken away;

Fig. 2 is a view partly in side elevation and partly in section and with some parts broken away showing a four branch pipe fitting and air venting tube incorporated therewith;

Fig. 3 is a view corresponding to Fig. 2 but illustrating the invention applied to a pipe fitting of the T type;

Fig. 4 is a sectional view illustrating a modification of the air closing cap and a portion of a pipe fitting; and

Fig. 5 is a fragmentary elevation of a modified arrangement.

Referring first to the structure illustrated in Figs. 1 and 2, the numeral 10 indicates a hot water heater or boiler as shown having hot water outlet pipes 11 and 11a and return pipes 12. The hermetically closed pressure tank 13 is shown as connected by a pipe 14 to one of the outlet pipes, to wit, the pipe 11.

The pipe coupling 15 is shown in Fig. 2 and has an externally threaded neck or nipple 16 and also has three internally threaded necks 17, 18 and 19. Either of the necks 18 or 19 at will may be closed by a plug 20. The threads of all four of the branches are shown as tapered and in this illustration a faucet or valve 21 is adapted to be applied either in the branch 18 or 19, in which case the plug 20 would be applied to the

neck or branch to which the faucet is not applied.

A cap 22, which has tapered internal threads, is adapted to be screwed on to the branch or nipple 16. The drain pipe 23, which extends from the bottom of the tank 13, is shown as screwed into the neck or branch 17.

The air venting pipe 24, which is much smaller than the pipe 23, is extended from the top or upper portion of the tank 13 downward through the drain pipe 23 and is bent and passed through an annular plug 25 applied to the interior of the nipple or neck 16. This plug 25 can be applied as shown and stated either by molding a solder or other metal into the interior of the said neck 16 and uniting the same with a fluid-tight joint both with the neck or air venting pipe. Obviously when the cap 25 is screwed tightly on to the tapered threads of the nipple 16, the passage of water from the fitting and the passage of air to the air venting tube will be cut off. However, with the tapered threads, if the cap be loosened so that there is leakage of air between the tapered threads, air will pass to the air venting tube 24, but this will not permit the escape of water until, of course, the faucet is opened, whereupon the water will be free to flow from the tank and air will be admitted to the tank to replace the outwardly flowing water.

As already indicated, the faucet can be applied at will to either of the internally threaded necks or branches 18 or 19.

In the structure illustrated in Fig. 3 the T-fitting 15a is provided with an externally threaded neck or nipple 16a and internally threaded necks or branches 17a and 18a. On to the externally threaded nipple 16a is screwed a cap 22a, and into the neck or branch 18a is screwed the threaded end of a faucet or valve 21a. In this structure the drain pipe 23a is screwed into the branch or neck 17a. The air venting pipe 24a, which is brought down through the drain pipe 23a, is passed through an annular plug 25a that corresponds to the annular plug 25 of the first described structure. In this modified arrangement the threaded cap 22a and the neck or nipple 16a have tapered threads so that the cap, when screwed tight, closes the air vent and, when loosened, admits air into the air venting pipe, substantially as in the earlier structure.

In some instances it may be desirable to apply the cap to the neck or nipple by means of closely engaging non-tapered threads; and for such an arrangement I employ a structure such as shown in Fig. 4. In this structure the neck or nipple

16b is provided with an annular plug 25b through which the air receiving end of the vent pipe 24b is passed as in the previously described structures. In this instance, however, the cap 22b is provided with an air vent 26 and with an axial boss or raised flat surface 27 which, when the cap is screwed tight, engages the end of air tube 24b and closes the same. With this structure for air venting purposes it is only necessary to slightly unscrew the cap so as to permit air to pass 10 between the surface 27 and the engaged inner end of the tube 24b or bushing 25b or both.

The air vent tank drain described may be very cheaply made and assembled and can make use of pipe fittings such as may be found on the market or easily obtained. In actual practice the efficiency of the device has been demonstrated.

In the modified structure illustrated in Fig. 5 the cap 22c, which corresponds to the cap 22b, can be left tightly screwed on to the body member. In this arrangement an air valve 28 is connected to the interior of the cap 22c by a coupling 29. With this arrangement valve 28 will be normally closed, but, when opened in the customary well known way, air will be admitted to the interior of cap 22c and, hence, through the air vent pipe to the top of the tank.

The tank, assumed to be the pressure tank of a heating system, may take various forms and, 30

in fact, may be a tank used for various different purposes but requiring draining and admission of air to facilitate the draining action.

What I claim is:

5. 1. A pipe fitting of the kind described provided with at least three branches, the first of which is internally threaded to receive the externally threaded end of a drain pipe; the second of which is internally threaded to receive the threaded shank of a faucet; and the third of which is externally threaded and internally plugged; a cap screw threaded onto the said externally threaded branch; and an air venting tube extended through said first internally threaded branch and 15 through the internally plugged end of said third or externally threaded branch; said cap when applied serving to close the outer end of said air venting tube.
2. The structure defined in claim 1, in which 20 said cap is provided with an air vent and with an axially located internal surface adapted to directly close the air receiving end of said venting tube.
3. The structure defined in claim 1 in which 25 said cap is connected to the co-operating externally threaded branch by tapered threaded engagement, whereby the cap will be opened to the atmosphere when loosened.

MELVIN N. JOHNSON.
